COIN BANK

Ernest D. Pirring, Struthers, Ohio

Application May 11, 1945, Serial No. 593,258

2 Claims. (Cl. 232—4)

1

This invention relates to coin savings banks and more particularly to small banks of this nature which are operative to prevent unauthorized removal of any of the coins until a predetermined number of coins have been deposited in the bank. The primary object of the invention is the provision of an improved coin bank of the general character specified which is operative to receive a plurality of different kinds of coins and which is provided with means to prevent the unauthorized removal of any of the coins until a predetermined composite total amount of all the coins is positioned in the bank. Thus, it is possible, in accordance with the invention, to construct coin banks in which any predetermined total amount of money, within reasonable limits, must be deposited before any of the coins previously deposited can be readily removed from the article.

A further object of the invention is the provision of a coin bank having the characteristics enumerated above which is exceedingly simple in design, very economical to construct, but which nevertheless is durable, serviceable, as well as interesting and pleasing in appearance.

Another and more specific object of the invention is the provision of a coin bank having a multiplicity of coin receiving wells and a common releasable cover therefor whereby a predetermined composite number of coins must be positioned in the bank before the cover may be removed. Further, the bank is so constructed that it consists of but two principal parts—a body member containing the wells and a common cover member aforesaid—both of which may be economically formed by the molding of glass, plastic, or other suitable material. The elements of the locking and release mechanisms are also simple in design, easily produced and assembled in and on the two principal parts of the assembly.

The above and other objects and advantages of the invention will become apparent upon consideration of the following detailed specification and the accompanying drawing wherein there is disclosed a representative embodiment of the invention.

In the drawing:

Figure 1 is a plan view of a coin bank constructed according to the principles of the invention;

Figures 2 and 3 are side and end elevations, respectively, of the coin bank of Figure 1;

Figure 4 is a transverse sectional view taken along the line IV—IV of Figure 2;

2

Figure 5 is a fragmentary horizontal section taken along the line V—V of Figure 2; and

Figure 6 is a longitudinal section through the upper half of the bank, the view being taken along the line VI—VI of Figure 3.

Referring to the drawing, reference numeral 10 designates the principal body member of the assembly and, as shown, this body member comprises essentially a block of material having three spaced vertically disposed coin receiving wells therein, designated by reference numerals 11, 12 and 13, respectively. Member 10 is preferably molded of glass, clear plastic, or other suitable transparent material so that the coins received in the wells can be viewed from outside the assembly. The wells 11—13 are of different diameters to receive different coins—for example, the well 11 being dimensioned to receive pennies, the well 12 to receive nickels, and the well 13 to receive dimes. The upper side edges of the body member 10 are rabbeted as shown at 14 in Figure 4 and one end wall is projected upwardly and formed with an overhanging lip 15, the purpose of which will become evident below. The opposite end wall of the body member 10 is formed adjacent its top end with an outwardly extending lug 16 (Figures 2 and 6).

To complete the housing I provide a cover member 17 consisting of a plate-like body also preferably molded of transparent material as, for example, a suitable clear plastic. Cover 17 has downwardly extending side lips 18 to fit within the rabbets 14 (Figure 4) and a transversely extending rabbet 19 to receive the lip 15 of the body member 10. In this manner the cover member 17 is held against lateral movement, against longitudinal movement in one direction, while one of its ends is held against vertical movement by the lip 15. Vertical movement of the opposite end of the cover 17 is prevented by an integral lip 20 (Figure 6) which engages underneath the lug 16 of the body member 10. The surfaces and interlocks thus far described prevent movement of the cover 17 in any direction other than longitudinal sliding movement of the cover in a direction away from the lip 15. Means now to be described is employed to releasably prevent such sliding movement.

Longitudinal recesses 21 are formed at diametrically opposed points in the side wall of each of the wells 11—13 and slidably mounted in such recesses are the rods 22 and 23, the former being longer than the latter and projecting up above the top ends of the latter. It should be observed that a pair of such rods 22, 23 is provided for

each of the wells and secured to the lower end of each such pair is a coin support having a tilted upper section 24 and a lower horizontal section 25. Interposed between the bottom of each well and the support section 25 housed therein is a coil spring 26 having sufficient strength to hold the rods 22 and 23 in upper position even though a full column of coins is resting on the support 24, 25. The upper ends of the rods 22 are normally received in detents 27 formed in the under surfaces of the cover 17. As illustrated in the drawing, the detents 27 are arranged in "saw-tooth" fashion so that upon the sliding application of the cover to the body member the rods 22 will be automatically depressed to allow the sliding movement to take place. As the cover 17 approaches its fully closed position, however, the upper ends of the rods 22 snap up into the deepest parts of the detents 27 and adjacent the vertical walls of these detents whereupon the cover 17 is locked against outward sliding movement until the rods 22 are depressed downwardly. Rods 22 are moved downwardly when the columns of coins associated therewith contain a predetermined number of coins. By referring to Figure 1, it will be evident that the rods 22 and 23 are aligned in a longitudinal plane passing through the axes of the wells 11-13. Further, since these rods are slidably received in recesses in the side walls of the wells the coins may be slipped into the wells transversely. While it is contemplated that the locking assemblies comprised of the rods 22, 23 and the coin supports 24 will be rigid enough to prevent flexing of the rods 22 when the wells contain but a few coins, the strength of the locking arrangement may be improved over that illustrated by interchanging the position of the rods 22 and 23 in each well so that flexing of the longer or locking rods is impossible. Of course, the positions of the detents 27 and the cover 17 would then be suitably relocated as will be understood.

Laterally aligned with each of the wells 11-13 is a groove 28 formed in the top surface of the body member 10 to one side of the well. The grooves 28 are of such width and depth as to closely receive the particular coin intended to be inserted therein, it being understood that the coin will be placed in a horizontal position and moved sideways when being inserted in the groove 28. The lower edge of the adjacent lip 18 of the cover member 17 is notched to provide passages for such progression of the coins and, as illustrated in Figure 4, the outer edges of the openings are rounded or "eased" to facilitate entry of the coins.

Associated with each of the wells 11-13 is a transversely extending leaf spring 29 having a center portion riveted or otherwise securely fastened to the cover member 17, a curved end portion 30 extending into the top of the well, and an opposite curved end portion 31 positioned just inwardly of the adjacent lip 18 of the cover member 17.

In using the coin bank above described the coins are inserted in the slots in succession, the succeeding coins pushing the coins ahead into the wells down which they fall to form stacks or columns resting on the supports 24. The parts are so dimensioned that normally but a single coin (as the coin 32 in Figure 4) lies in each of the slots and the function of the spring detents 31 is to prevent outward sliding movement of the coins held in the slots. As the columns or stacks build up the tops approach the springs

30 which are somewhat stronger than the springs 26. Now as coins begin to be wedged between the tops of the stacks and the springs 30 the stacks move downwardly against the forces of springs 26 thus lowering or retracting the locking rods 22. When the latter have been moved downwardly sufficient to clear the adjacent vertical walls of the detents 27 the cover member 17 may be slid off the body member 10 as will be apparent. In practice, the parts are so dimensioned that a predetermined number of coins must be in the stacks or columns before the rods 22 release the cover. It should be observed that a deficiency of coins in any one of the wells will hold the cover locked against removal. By simply cutting the rods 22 and 23 to the proper lengths the bank may be prepared to retain any predetermined total sum of money before releasing the cover member 17.

It should now be apparent that I have provided a coin bank possessing such embodiments as accomplish the objects initially set out. While the invention is particularly concerned with a multiple well arrangement it should be understood that various features are equally applicable to a smaller bank employing but a single well. In any embodiment the same simplicity and economy of construction and assembly is inherent in that the two principal parts of the assembly may be readily cast or molded and the other operative elements of the assembly mounted on these principal parts before the same are put together. It is contemplated that suitable indicia may be imprinted on the body member, 10 and/or on the cover member 17 in association with the coin receiving slots to indicate the proper slot for receiving a particular coin.

The above specifically described embodiment of the invention should be considered as illustrative only as obviously many changes may be made therein without departing from the spirit or scope of the invention. Reference should therefore be had to the appended claims in determining the scope of the invention.

What I claim is:

1. A coin bank comprising in combination a body member having a plurality of coin receiving wells therein, a cover member having a plurality of locking detents and adapted to be detachably secured to said body member in locked relation therewith thereby closing off said wells to prevent unauthorized removal of coins therefrom, a restricted passage associated with each of said wells whereby individual coins may be inserted in succession in said wells, and a locking member in each of said wells having an integral extending portion engaging a respective detent in said cover member thereby preventing removal of said cover member, each of said locking members having means to retract said portion upon the insertion in the well associated therewith of a predetermined number of coins.

2. A coin bank comprising in combination a body member having a coin receiving well therein, a cover member having a locking detent and adapted to be slid into position on said body member thereby closing off said well to prevent unauthorized removal of coins therefrom, said well having a recess extending up along its side wall, a rod in said recess movable from upper to lower positions and operative when in upper position to engage said detent of said cover member to restrain the same against sliding movement, a coin support secured to the lower end of said rod and spanning said well, a spring in the lower por-

tion of said well urging said support and rod upwardly, a curved leaf spring at the upper end of said well against which coins may wedge to move a stack of coins resting on said support downward against the force of said first mentioned spring thereby moving said rod downwardly, and means providing a passage for the insertion of coins sideways into the upper portion of said well.
